UNITED STATES PATENT OFFICE.

JACOB DAVID, OF BROOKLYN, NEW YORK, ASSIGNOR OF ONE-HALF TO
EDWARD A. DEVEAU, OF SAME PLACE.

AUTOMATIC CAR-BRAKE.

SPECIFICATION forming part of Letters Patent No. 279,136, dated June 12, 1883.

Application filed October 24, 1882. (No model.)

To all whom it may concern:

Be it known that I, JACOB DAVID, a citizen of the United States, residing at the city of Brooklyn, in the county of Kings and State of New York, have invented a new and useful 5 Automatic Car-Brake, of which the following is a specification.

My invention relates to automatic or self-acting auxiliary or supplemental brakes to be attached to cars, in addition to the ordinary steam, air, or hand brakes at present in common use on cars, whereby when the car meets an obstruction of any kind on the railroad-track the obstacle will be pushed away from the 10 wheels of the car and instantly and automatically arrest the progress of the car, and also, by the addition of a lever attached to the car and to the said auxiliary brake, to enable the brakeman or driver to bring the car to a 15 standstill instantaneously at any desired place. I attain these objects by the mechanism illustrated in the accompanying drawings, in which—

Figure 1 is a side elevation, showing a section of a car with my automatic brake attached thereto. Fig. 2 is a plan view of the under side of a car, showing the automatic brake in place.

Similar letters refer to similar parts in the two figures.

A is a section of a car.

B B are the car-wheels.

C is the shoe of the common or ordinary car-brake as at present in use.

35 D' D² are the shoes of my automatic car-brake, which are formed of a strip of iron or steel, pivoted at one end to a connection-rod, E' E², on each side of the car. One of these 40 brake-shoes, D', is placed in front of one of the front car-wheels over one of the rails of the track, and the other brake-shoe, D², is placed in front of the other front car-wheel on the other side of the car and over the other rail of the track. These brake-shoes D' D² are about 45 the same in width as the width of the face of the car-wheels. One end of the rod E' E² is pivoted to the brake-shoes D' D², and the other end of said rod is carried over the brake-shoes C C, through the slot I, across the width of the 50 car, the center or middle portion of said rod being connected to the yoke N; or said rod may

be pivoted to the car at any other convenient point, provided said brake-shoes have sufficient play to enable them to reach to within three or four inches of the rails of the track. The 55 free ends of the brake-shoes D' D² are held off and away from the track by the chain S, which has one end attached to the bar F at its center, and the other end of said chain is attached to the bar Q, which latter bar connects the 60 brake-shoes C C.

G is a spiral spring, one end of which is connected to the yoke N, and the other end is connected to the under side of the platform of the car. This spring G is only of sufficient 65 strength and tension to keep the brake-shoes D' D² from under the wheels in the position shown in Fig. 1.

M is a bar extending across the entire width of the car at the extreme end, and is connected to the car by a pivoted rod, L, on each side of the car.

K is a horizontal rod, one end of which is pivoted to the bar M, and the other end is pivoted to the yoke N.

P' P² are braces, which are rigidly attached underneath the frame of the car, near the end, and just back of the bar M, and against which the bar M will strike when it comes in contact with any obstruction.

75 Q is a lever pivoted at its lower end to the bar M, and pivoted at its middle portion at the point marked R at the front end of the car-platform, as shown in Fig. 1.

F is a horizontal bar which extends entirely 80 across the front of the car, and serves as a support and connection for the brake-shoes D' D².

H is the rod which supports the brake-shoes C C and holds them in place in front of the 85 wheels of the car.

90 The different parts having been constructed and connected together and attached to the front or either or both ends of the car, the manner of operation is as follows: When the car is in motion, any obstruction which is 95 small enough to pass underneath the steps of the car is struck by the bar F, which is connected at each end to the brake-shoes D' D², or is struck by the rod E' E². In either event the brake-shoes D' D² are driven against the 100 wheels and between the wheels and the rails of the track, and the car-wheels are thereby

caused to run up and upon the brake-shoes D' D² in the position shown by the dotted lines in Fig. 1. The wheels then cease to revolve and the dead-weight of the car causing an immense friction between the under sides of the brake-shoes D' D² and the face of the rails, the car is instantaneously stopped. When any large obstruction—as, for instance, a horse—suddenly falls in front of the car while the latter is in motion, such obstruction will strike against the bar M, which bar, being connected by the pivoted rod K to the yoke N, and the yoke N being connected to the rod E' E² and the brake-shoes D' D², causes said brake-shoes D' D² to be driven back against and between the wheels and the rails, as shown by the dotted lines in Fig. 1, causing the same cessation of the revolution of the wheels, and the consequent friction between the brake-shoes D' D² and the rails, and the instantaneous stoppage of the motion of the car, as before stated, and the rigid braces P' P² prevent the bar M from being pushed back farther than said braces, as is shown by the dotted lines in Fig. 1. These actions just described are automatic, and are entirely independent of the brakeman or driver; but by the use of the lever O, heretofore described, and shown in Fig. 1, attached to the front platform of the car, the brakeman or driver can, by pushing the end of the lever O away from him, cause and produce the same effect as in the two previously-described operations. This lever O may be made a jointed lever with two fulcra, which, when pulled toward the brakeman or driver instead of being pushed from him, will produce the same action of the brake-shoes heretofore described. When from any of the causes heretofore described, the car is stopped with the brake-shoes D' D² between the wheels and the rails, as shown by the dotted lines in Fig. 1, the wedge shape of the ends of said brake-shoes, together with the recoil of the car, causes the wheels to back off from the shoes, and the spiral spring G draws the apparatus back to its original or first position, as shown in Figs. 1 and 2.

It is not my design in the use of the apparatus herein described to supersede or do away with any of the car-brakes at present in use which are operated by steam, air, or hand power, but to apply the same as an automatic auxiliary or supplement to such brakes for the

purpose of affording a means of instantaneously stopping a car when it comes in contact with an obstruction while in motion, whether the other steam, air, or hand brakes are in use or not; and

What I claim as my invention, and desire to secure by Letters Patent, is—

1. The arrangement and combination of the brake-shoes D' D² with a swinging and connecting rod, E' E², said connecting-rod having a yoke, N, in the center to which yoke a spring, G, is attached, as shown, having an obstruction-bar, F, connecting at one end to the connecting-rod at E' and connecting at the other end to the end of the connecting-rod at E², thus being placed across the width of the car in such a manner that both shoes D' and D² will each be driven under a wheel on both sides of the car at the same time, and having a chain, S, to sustain the brake in position, substantially as shown and described.

2. A car-brake having the brake-shoes D' D², jointed to the connection-rod E, and the obstruction-bar F, connected to the rod at E' and E², having a yoke, N, on the connection-rod E, with the tension-spring G and sustaining-chain S, as described, in combination with a hand-lever, O, with a connecting-rod, K, for the purpose as shown and described.

3. A car-brake composed of the brake-shoes D' D², jointed to the connecting-rod E' E², and the obstruction-bar F, having a yoke, N, on the connecting-rod E, with a sustaining-chain, S, and tension-spring G, as described, in combination with a front obstruction-bar, M, placed on the extreme front end and across the front of the car, and connected to the car by the swinging rods L, and connected to the yoke by the jointed bar K, having the rigid braces or stops P' P², for the purpose as shown and described.

4. A car-brake having the obstruction-bar M, connected to the brake-shoes D' D² by the bar K, and connection-rod E' E², having a yoke, N, with a tension-spring, G, and a sustaining-chain, S, all arranged in the manner described, in combination with a hand-lever, O, for the purpose as shown and described.

JACOB DAVID.
